COMPRESSOR

William W. Wishart, Chicago, Ill.

Application February 9, 1935, Serial No. 5,712

9 Claims. (Cl. 230—140)

My invention relates in general to fluid-flow apparatus including pumps and motors and has more particular reference to a rotary device especially well adapted for use in the compression of fluids.

An important object of the invention is to provide a fluid-flow device, more particularly a pump or compressor, of simplified construction and having improved means for preventing leakage from and in the device and for adjusting the operating clearances of the working parts to permit the device to operate at maximum efficiency in the development of unusually high pressures in the work medium.

With machines embodying the features of my present invention, I have been able to compress as well as exhaust various work media, such as air, ethyl chloride, ammonia, and other gases to pressures substantially greater than has heretofore been considered practical with any degree of efficiency.

Another important object is to provide standardized parts from which may be constructed a compressor having any desired number of cylinders or stages, my invention providing for the construction of a single cylinder device; or a multi-cylinder device may be constructed by the mere multiplication of standard parts in the assembly, but two conversion parts of a form not necessary in the single cylinder assembly being required in each cylinder in the assembly in excess of one.

Another important object is to provide a multi-cylinder device of the character mentioned having a separate inlet for each cylinder and a common discharge from the device.

Another important object is to provide a multi-cylinder compressor, the cylinders of which are adapted to receive the work medium at different pressures at their respective inlets and to deliver the work medium at the same pressure at their outlets.

Another important object is to provide an hydraulic or fluid-forcing device having facilities for lubricating the operating parts, including a built-in lubricant pump; a further object being to form the pump within the casing of the compressor and to arrange for driving the pump and one of the co-operating compressor elements from a common shaft within the casing.

Another important object is to provide a fluid-forcing device or compressor including a built-in lubricant pump within the compressor casing and including an external lubricant system connected to deliver lubricant to the pump and to withdraw

lubricant from a remote part of the compressor casing to which the lubricant is or may be circulated by the operation of the pump.

A further object is to drivingly connect the lubricant pump on the shaft within the casing whereby to assist in sealing the shaft at its point of emergence.

A still further object is to provide a device of the character described including a cylinder having a radial duct in an end wall thereof and a channel extending axially of the cylinder either through an axle on which the cylinder is carried or through a support on which a piston is mounted within the cylinder, said channel communicating with the duct so that a work medium may travel progressively through the channel, duct, and cylinder.

Another object is to provide a device of the character mentioned having a passageway for a working medium, said passageway communicating with the interior of the cylinder and extending thence radially in an end wall of the cylinder and then axially of said cylinder, either in the cylinder axle or in a piston support extending within the cylinder.

Another important object of the invention is to provide, in fluid-flow apparatus of the character mentioned, wherein fluid is delivered to or from the work chamber through communicating channels, one extending radially in the cylinder wall and another axially in the piston support, the combination of a seal carried by one of the co-operating elements or its support and lapping on the other and adapted to prevent fluid leakage to or from the channels at their point of communication.

A further object is to form the seal as a self-seating, self-lapping element carried by one of the co-operating elements on its support and having wiping engagement with the other element at the opening of the communicating channel therein.

Another important object is to provide an annular seal having eccentric movement with respect to the surface with which it has sealing engagement.

Numerous other objects, advantages, and inherent functions of the invention will be apparent from the following description, which, taken in connection with the accompanying drawings, discloses a preferred embodiment of the invention.

Referring to the drawings:

Figure 1 is a sectional view taken through a fluid-flow device embodying my present invention;

Figures 2, 3, and 4 are sectional views taken substantially along the lines 2-2, and 3-3 in Figure 1, and line 4-4 in Figure 3, respectively;

Figures 5 and 6 are perspective views illustrating parts of the device;

Figures 7, 8, and 9 are sectional views showing modified arrangements of the apparatus embodying my invention;

Figures 10 and 11 are sectional views taken substantially along the lines 10-10 and 11-11 in Figures 8 and 9 respectively.

To illustrate my invention, I have shown on the drawings a fluid-flow device comprising a rotary machine especially well adapted to function as a pump or compressor for a gaseous medium, although it will be obvious that the invention has application in any type of fluid flow apparatus.

Apparatus, embodying my invention, however, is characterized by the novel arrangement of fluid inlet and outlet conduits, including the arrangement of a conduit extending radially in a cylinder wall and communicating with an axially extending channel which may be formed either in the axle of the cylinder or in the axially extending support on which the piston is carried. In the construction wherein the channel extends in the piston support, I have also provided novel means for sealing communicating channels formed in the relatively moving parts, the seal being formed and arranged in such a way as to move relatively and engage a larger surface of the element with which it has sealing engagement than the contacted area of the seal, whereby the seal continuously laps the surface on which it is seated and thus maintains the sealing surfaces in smooth evenly polished condition.

I also provide improved means for lubricating the operating parts of the apparatus, including the self-lapping seal, said means including a built-in lubricant pump having a fluid-forcing element in co-axial alignment with and mounted on a shaft common to one of the co-operating elements of the compressor.

I have employed these improvements for the purpose of illustrating the invention in a fluid-flow apparatus, which has further novel features, the invention including the provision of a rotary fluid flow device, which can be constructed either as a single or multi-cylinder or stage device by merely adding a minimum number of standard parts in the assembly.

To accomplish the foregoing, I utilize certain novel structural arrangements including not only the particular form of the parts employed but also the co-operation of said parts with each other as well as with the improved lubricating means whereby the operating parts of the device are properly lubricated and sealed against leakage.

The device, which I have shown for the purpose of illustrating the invention, comprises co-operating elements including cylinder means 11 and piston means 13, which are mounted for relative movement in order to accomplish the hydraulic function of the device. The cylinder and piston means are mounted in a frame or casing 15 and are preferably mounted for rotation on the frame about relatively eccentric though parallel axes. The piston means comprises one or more cylindrical elements 13, which are mounted within cylindrical portions 19 of the cylinder with the peripheral surfaces of the piston means in contact with the inner surface of the cylindrical wall portions 19 of the cylinder. Since the inner diameter of the cylindrical wall portions 19 is

larger than the diameter of the piston means 13, a crescent shaped work space or spaces 21 is defined between the cylinder and piston means.

The frame or casing 15 provides a closed housing in which the elements 11 and 13 are mounted and the work medium is delivered into the work chamber or chambers 21 through a channel 23 extending axially through the piston means 13 and thence radially in a duct 25 formed in the walls defining the cylinder means. The casing 15 preferably comprises co-operating parts one of which provides a base 27, and wall portions 29 forming a preferably cylindrical compartment opened at one end. The casing also includes a member 31, forming a cover adapted to close the open end of the compartment, said cover being preferably formed as a substantially circular plate having peripheral portions 33 adapted to co-operate with the edge portions 35 defining the casing opening. The casing portions 33 and 35 are preferably provided with co-operating tongue and groove means comprising, in the illustrated embodiment, a groove 37 in the portion 33 and a co-operating tongue 39 on the portion 35, so that when mounted the cover 31 is properly aligned with respect to the casing portion 29 by means of the inter-engagement of tongue 39 in the groove 37.

The casing parts 29 and 31 are designed to provide a chamber of size sufficient to receive a single cylinder hydraulic element. Where it is desired to assemble a multi-cylinder device, I provide means for enlarging the casing 15, said means comprising an annular ring or rings 41 adapted to be assembled between the casing portions 33 and 35, a ring 41 being employed for each additional cylinder in the assembly, said rings being of a width equal to the increase in length imparted to the cylinder means 11 by the addition of a stage. Each ring 41 is formed on its opposite faces with tongue and groove means 43 and 45 adapted to co-operate with the tongue and groove means 37 and 39 between which said rings are arranged. Sealing gaskets 47 are also preferably applied at said tongue and groove means for the purpose of sealing the casing. The cover 31 and the ring or rings 41, if used in the assembly, are secured on the wall portions 35 of the casing part 29 by any suitable fastening means such as the studs or bolts 49, said bolts penetrating perforations formed in the peripheral portions 33 in the cover and in the annular rings 41 and threading into openings formed in the annular wall portion 35.

The cylinder means 11 comprises a pair of end plates 51 and 53 arranged in spaced facing relationship with the cylinder portions 19 extending between the peripheral portions of said plates. The cylinder portions 19 comprise annular rings, there preferably being a separate ring for each compression stage or cylinder in the device, the rings 19 being separated from the adjacent ring by a partition 55, although, where a single stage device is assembled, the partition 55 may be omitted entirely. The rings 19 and partition 55 means 55 are arranged in stacked relationship between the end plates 51 and 53 and the entire assembly is clampingly secured together in any suitable fashion as by the fastening means 57, comprising co-operating nuts and bolts, said bolts penetrating a circular series of spaced perforations formed in alignment circumferentially on the end plates, rings, and partition means in order to clamp the parts together. In order to support the co-operating parts 11 and 13 in op-

erating position within the casing 15, I provide an axle 59 for the cylinder means 11, said axle being attached to the end plate 51 so that the axis of the axle is in line with the geometric center of the cylinder, that is to say, the axle 59 is in alignment with the central axes of the cylindrical inner surfaces of the annular rings 19. The axle 59 extends in an extension 61 formed on the cover 31 and is journaled for rotation in bearings 63 and 65 in said extension.

The outer end of the extension 61 is provided with a cover 62 secured in place in any suitable fashion as by the holding studs 64, said cover having a central opening defining the journal 65, through which the axle 59 extends outwardly in position to be operatively associated with a driving device or motor for the purpose of rotating the cylinder means within the casing.

The end plate 53 of the cylinder means 11 is 20 mounted in any suitable fashion on the casing walls 29, said walls being preferably formed with an integral sleeve 67 adapted to extend within a central opening formed in the end plate 53 in order to support the plate for rotation on said 25 sleeve. Suitable bearing means 69 is preferably interposed between the end plate and the sleeve 67, on which it is supported.

The piston forming means 13 are mounted on an axle 71, which is supported in the frame 15 in position extending within the cylinder means 11 through the central opening in the end plate 53, said axle 71 being supported in an opening formed in the sleeve 67, said opening being eccentric with respect to the axis of rotation of the 30 cylinder means. The portions of the shaft 71, which extend within the cylinder means 11, are arranged to support bearings 73 of any suitable or preferred construction by means of which the piston forming means 13 are rotatably carried on 35 the shaft 71. The portion of the shaft 71, on which the piston-forming means is carried, is eccentric with respect to the shaft portion supported in the sleeve 67. The eccentricity of these shaft portions, however, is less than the eccentricity of 40 the axis of the cylinder means with respect to the supported portions of the shaft 71 so that by turning the shaft 71 in the sleeve, the eccentricity of the piston within the cylinder may be adjusted and the clearance between the piston and cylinder 45 at their point of peripheral contact accurately adjusted from outside of the casing. The cylinder and piston supports consequently need not be located in the frame or casing with any particular degree of accuracy.

In order to provide for the convenient adjustment of the piston in the cylinder in the manner just described, the shaft portion 75 extends outwardly of the wall 29 through a preferably threaded embossment 77, the projecting end of the shaft 50 being also preferably threaded as at 79 to receive a nut 81 by which the shaft may be locked in adjusted position. The projecting end of the shaft is formed with a preferably non-circular portion 83 adapted to receive a turning instrument where- 55 by to rotate the shaft in adjusting the same in the sleeve 67. I also provide a removable cover comprising a cap 85 adapted to be threadingly secured upon the embossment 77 in order to enclose and protect the outer end of the shaft 75 and 60 to prevent fluid from escaping from the casing through the sleeve 67 and the embossment in which the shaft 75 is carried.

The arrangement for adjusting the clearance between cylinder and piston is not, of course, 65 necessarily restricted to a device of the form

herein illustrated and may, of course, be applied in any rotary device requiring adjustment. Furthermore the invention herein is not necessarily restricted to a fluid forcing device or compressor having the piston adjustment herein illustrated 5 and described. On the contrary, any suitable or convenient means may be utilized for the adjustment mentioned.

In the illustrated embodiment, the piston means 13 is mounted on the eccentric portion 74 10 of the shaft 71, suitable anti-friction bearings 73 being interposed between the shaft portion 74 and each of the pistons. Each piston comprises a cylindrical block as shown in Figure 6 having an axial opening 87, through which the shaft 15 portions 74 extend. It will be understood, of course, that the shaft 71 used in a single cylinder assembly will be cut off and finished at its inner end substantially as shown at 89^a and that the length of the portion 74 is dependent upon the 20 number of cylinders in the assembly. In a multi-cylinder assembly, the shaft portion 74 extends through an opening 91 in the partition means 55 intermediate adjacent cylinders so that the pistons 13 of adjacent cylinders are disposed upon 25 opposite sides of the partition 55.

While I have shown my present invention as applied in a rotary compressor in which both the cylinder and piston are rotated in order to deliver the work medium through the work space 30 21, it will be obvious that the invention may be applied in any arrangement wherein relative movement is imparted to the piston and cylinder means 11 and 13 in a manner to cause the work space 21 to circulate relatively around the cylinder and, therefore, I do not wish necessarily to limit the invention to a device in which both the cylinder and piston means rotate.

I prefer, however, to arrange the parts so that the cylinder at least rotates on its axle 59 while 40 the pistons 13 rotate on the shaft 71. Where the device is used as a pump or compressor, the axle 59 will be connected for rotation by a prime mover such as an electric motor while the pistons are driven by an operating connection formed 45 between the pistons and the cylinder. To this end, the cylinder assembly carries a blade 89 extending in a substantially radial direction, said blade having its outer edge secured in aligned notches 91 formed in the inner surface of the 50 cylinder rings 19. The blade is long enough to extend between the end plates 51 and 53 and to be snugly clamped therebetween when the fastening devices 57 are tightened. If desired, the end plates may be provided with grooves for receiving the opposed ends of the blade. The blade is thus held tightly by and between the end plates so that leakage of the work medium between the edges of the blade and the contacting 55 surfaces of the end plates and rings 19 is prevented. The blade also extends snugly through an opening 93 in the partition 55 so that the opposite sides of the plate extend in adjacent 60 cylinders of the assembly.

The blade extends in substantially radial slots 65 95 formed in the pistons 13 so that rotation of the cylinder by means of a shaft 59 will cause rotation of the pistons through the driving connections provided by the blade. It is, of course, within the confines of my invention to provide for 70 driving the pistons instead of the cylinder, in which case the cylinder element 11 will be driven by the rotation of the piston, through the driving connection provided by the blade. In either event, since the cylinder means 11 and piston 75

means 13 are mounted for rotation about relatively eccentric axes, the work spaces 21 in each cylinder will, upon rotation of the parts be caused to travel relatively around the circumference of 5 the rings 19. The blade 89, however, travels with the cylinder assembly so that the operation of the parts will result in the development of unequal pressures in the work spaces in each cylinder on opposite sides of the blade 89, depending upon the 10 direction of rotation of the parts. For example, if the parts are rotated in a counter-clockwise direction, viewing Figure 3, pressure will be relatively reduced on the left hand side of the blade and will be increased on the right hand side of 15 the blade. Conversely, if the rotation is clockwise pressure will be reduced on the right hand side of the blade and increased on the left hand side.

The device illustrated is adapted to function 20 as a compressor and to be driven in a clockwise direction, viewing Figure 3. I consequently provide an inlet port 97 opening into the cylinder on the right hand side of the blade 89. If desired, these ports may be provided with valve means 25 opening inwardly into the cylinder and the ports are connected by means of a duct 99 comprising aligned openings formed in the rings 19 and the partition 55. This duct 99 is connected with the radial duct 25 formed in the end wall of the cylinder so that the fluid medium introduced through the duct 25 may be delivered to the inlet port of each cylinder. The inner end of the radial duct 25 is preferably in communication 30 with the channel 23, which is formed axially in the piston carrying shaft 71. This conduit 23 communicates with the duct 25 at the inner end of the shaft 71, the end plate 51 having an opening 103 opposite the inner end of the shaft. The duct 23 extends in the shaft 71 axially from the 35 inner end of the shaft toward the opposite or projecting end of the shaft and communicates with a chamber 105 formed in the wall portion 29 at the sleeve 67, which carries the shaft 71. The duct 23 communicates with the chamber 105 through a lateral opening 107 formed in the shaft 71. The casing wall 29 is also formed with a duct 109 communicating with the chamber 105 and opening outwardly of the casing to form a 40 compressor inlet 111.

Upon operation of the device as a compressor, 50 the fluid work medium will enter the compressor through the inlet 111 and travel thence through the duct 109, the chamber 105 and thence through the channel 23 into the radial duct 25 and be delivered into the manifold duct 99 to the suction ports 97, thence the medium travels through the compression spaces in the several cylinders and is discharged through outlet ports 113 formed in the rings 19 on the left hand side of the blade, 55 viewing Figure 3. The ports 113 discharge into the housing 15, which is provided with a compressor outlet 115, through which the compressed medium may be delivered.

I prefer to provide outwardly opening valves 60 for the ports to prevent the return of discharged fluid through said ports into the cylinders. To this end, the ports 113 at their outer ends each carry a sleeve-like insert 119 forming a valve seat 121 for a flap valve 123. The flap valves for 65 adjacent ports may comprise a single strip of resilient material secured at its mid-point on the partition 55 with the ends of the strip extending in position to overlie the valve seats 121. I also provide a stop 125 for limiting the opening 70 movement of the flap valves from their re-

spective seats, said stop and the strip forming the flap valves being secured on the partition in any suitable manner as by means of the fastening device 127.

If it is desired to use the device as a fluid motor, 5 the fluid medium will be delivered under pressure through the inlet 111 and delivered to the inlet ports 97 through the channels 109, 23, 25, and 99. The pistons and cylinders will thereupon be caused to rotate in a clockwise direction, 10 the fluid medium traveling through the work space 21 and being discharged through the outlet ports 113 into the casing and thence through the outlet 115.

In order to seal the channel 23 and the duct 15 25 at their point of connection, it being remembered that the channel is formed in the stationary shaft 71, while the duct 25 is formed in the end plate of the rotating cylinder, I provide improved running seal means between said 20 parts comprising a sleeve 129 fitted into the end of the shaft 71 and forming an extension of the channel 23, said sleeve projecting at the inner end of the shaft and being threaded or otherwise sealed thereto. The sleeve carries an annular 25 sealing ring 131 on its projecting end, said seal ring comprising a cup-shaped element adapted to contain a sealing gasket 133 for the purpose of sealing the space between the ring and the sleeve. The end of the shaft 71 is recessed around the 30 sleeve and a spring 135 is mounted in the recess in position to compress the gasket into the seal ring and to yieldingly urge the ring in an axial direction outwardly on the sleeve into wiping engagement with the face of the end plate around the opening 103. When the cylinder rotates, the ring 131 provides a running seal preventing the escape of the work medium at this point.

It will be noted that the end plate 51 rotates 40 about an axis eccentric with respect to the central axis of the seal ring so that the latter engages an area of the end plate substantially larger than the area of the ring. The relative motion of the seal ring on the end plate provides a wiping effect between the parts, the ring continuously 45lapping the surface of the end plate and serving to maintain the sealing surfaces in highly polished condition.

Where the device of my present invention is 50 embodied as a pump or compressor for use in forcing fluid media containing or comprising a suitable lubricant, it may not be necessary to provide for lubricating the apparatus other than by utilizing the working medium itself. Where the device is used in connection with a work 55 medium which does not itself provide lubrication, I prefer to incorporate a lubricating system and to this end have shown a lubricant circulating system built into the device. The lubricating system comprises circulating means namely a pump 60 137 drivingly connected with the axle 59, although, of course, a separately driven pump may be employed if desired. I prefer, however, to utilize a rotary pump comprising an annular stator or cylinder 139 held between end plates 141 and mounted within the extension 61 of the casing. The stator and end plates are preferably held together in place in the extension in any convenient manner as by means of the studs 143, which hold the parts together and the studs 145, 70 which hold the pump assembly upon a partition 147 formed within the extension 61. The partition 147 has an opening defining a bearing 149 through which the shaft 59 extends and the partition divides the extension 61 into a compartment 75

151 extending between the cover plate 62 and the partition and a second compartment containing the pump 137 and the anti-friction bearing 63. The cylinder ring 139 and the end plates 141 form a compression space in which an annular rotor or fluid-forcing element 153 is mounted for operation, said rotor being splined on the shaft 59 and having an outer surface relatively eccentric with respect to the inner surface of the ring 139.

10 The compartment 151 forms a seal chamber and the facing surfaces of the partition 147 and the end plate are formed with embossments encircling the shaft 59 and adapted to receive sealing devices 152, which are forced apart in position riding on the embossments by means of a spring 154 extending between the sealing devices. The seal chamber in the forms shown in Figures 1 and 7, comprises a reservoir for a lubricant. In the embodiment shown in Figure 8, however, 20 the chamber 151 is connected with the duct 25 and serves as an inlet chamber for the fluid medium, the duct 25 being connected at its inner end through the channel 101, which extends axially in the shaft 59 and opens laterally of the 25 shaft through a radial bore 104 into the chamber 151. The chamber is provided with an inlet 102 so that the work medium may be delivered to the cylinders of the compressor along the path provided by the chamber 151, the port 104, the duct 101, the radial duct 25, and the manifold 99 leading to the inlet ports 97.

With the arrangement shown in Figure 8, I am able to eliminate the duct 23 in the shaft 71, the channel 109, and the chamber 105 in the walls 35 of the casing and also the wiping seal 131 and the mounting therefor. I find also that this arrangement, whereby the channel 101 opens in the chamber 151 instead of continuing in the shaft 59 and opening outwardly of the cover 62, 40 affords a simple and less expensive manner of introducing the work medium to the compressor.

In the forms shown in Figures 1 and 7, the lubricant is delivered into the chamber 151 either directly through the pipe 183, as shown in Figure 1, in which event an inlet duct 159 is formed through the partition 147 to convey the lubricant from the chamber 151 to the pump 137, or, as shown in Figure 7, the lubricant may be delivered by the pipe 183 directly to the pump, which in 50 this case is mounted in the compartment 151, the lubricant traveling a duct 160 formed in the partition 147, thence through a duct 160a in one of the end plates 141 of the pump 137. Lubricant is discharged from the pump through a duct 162 55 into the chamber 151 under pressure and enters a longitudinal duct 155 formed in the axle 59 through a radial channel 164.

As an alternate arrangement, the ducts 162 and 164 may be omitted and the pump arranged 60 to discharge directly into the duct 155 so that the lubricant need not necessarily be delivered into the chamber 151. In fact, where the chamber 151 is used, as shown in Figure 8, as an intake for the work medium, it is ordinarily undesirable to admit the lubricant to the chamber 151, because of the danger that the lubricant will be drawn into the compression cylinders along with the work medium. In certain cases, however, it may be desirable to deliver lubricant into the chamber 151 along with the work medium.

The rotor 153 is formed with a substantially radial duct extending inwardly from the periphery of the rotor and communicating with a longitudinal duct 155 formed in the shaft 59. The 70 rotor also carries a fluid-forcing vane 157

mounted on the periphery of the rotor adjacent said radial duct and adapted to bear upon the inner surface of the cylinder ring 139, so that, upon rotation of the element 153 in a counter-clockwise direction viewing Figure 2, lubricant 5 will be drawn from the chamber 151 through a duct 159 formed in the partition 147 and one of the end plates 141 and discharged into the duct 155.

The lubricant pump is first assembled in the extension 61 and the bearing 63 fitted to the shaft 59. The cover 31 may then be applied to the shaft 59. As the cover studs 49 are tightened, the sleeve or extension 61 is drawn onto the bearing 63, which in turn is forced along the shaft 59, 15 the frictional resistance of the parts causing the shaft and cylinder to move toward the right, viewing Figure 1, until the bearings 63 and 69 assume final assembled position. In this way, the cylinder means 11 is properly positioned within 20 the casing as an incident to the application of the cover 31.

When the axle 59 rotates, it turns the element 153 of the lubricant pump, thus drawing the lubricating medium from the chamber 151 and 25 forcing it into the duct 155 in the axle 59. This duct 155 communicates with another lubricant duct 161 formed in the end plate 51 and opening in a chamber 163 formed by relieving the inner 30 face of the end plate around the seal ring so that lubricant under pressure may be delivered behind the seal ring and serves to force the seal into sealing engagement as well as to lubricate the same. The chamber 163 communicates with the axle opening 87 of the adjacent piston so that 35 the bearing 73 may receive adequate lubrication from said chamber. The pistons are provided with ducts 165 extending from the opening 87 to an annular chamber 167 formed in each piston. The opposite side walls of each piston are formed 40 with openings 169 which communicate the chambers 167 with the partition 55 and with the end plates so that lubricant delivered in the annular chambers 167 through the ducts 165 may be applied to the contacting surfaces of the piston and 45 the partition and end plates. If desired, the partition may be provided with openings 171 between the pistons. Each piston is preferably provided with a duct 173 extending between the opening 87 and the slot 95 to deliver lubricant to the blade 50 89. Bearing 69 receives its lubrication by seepage of lubricant from the end of the chamber provided by the openings 87 in the pistons and the sleeve-like support 67 contains a duct 175 extending from an end of said chamber to a 55 lubricant outlet 177 formed in the wall 29. I prefer to connect the outlet 177 in any suitable fashion with the chamber 151 in order to complete the circulating system. In the embodiment illustrated, the outlet 177 is connected by means of a 60 pipe 179 to a reservoir 181 in which the lubricant may be cooled.

The reservoir has a suction pipe 183 communicating with the suction chamber 151 so that when the device is in operation, the lubricant is drawn 65 from the reservoir into the suction chamber 151 and then is delivered under pressure by the forcing pump 137 into the compressor as previously described and then is returned from the compressor to the reservoir 181. Some of the lubricant will, of course, escape from the compressor element and enter the casing 15, such lubricant will collect in a sump 185 formed in the bottom of the casing 15 and will drain into the reservoir 181 through a connection 187.

Since the blade 89 is fixed with respect to the cylinder to prevent leakage between the edges of the blade and the cylinder, it is obvious that the blade will have a relatively tilting movement 5 with respect to the pistons during the operation of the device and I form the opposite sides of the slot 95 with recesses 189 adapted to receive preferably semi-cylindrical bearing blocks 191. These bearing blocks have flat surfaces facing 10 the blade and between which the blade has reciprocating movement during the operation of the device. The bearing blocks also may rock in the recesses 189 in order to permit the blade to tilt relatively with respect to the piston while 15 at the same time maintaining a surface contact with the flat surfaces of the bearing block. I also provide an extension 193 in one of the recesses behind the bearing block, said extension 193 being adapted to receive means to yieldingly 20 urge the bearing block at all times toward the blade. This urging means may comprise a block 195 adapted to seat in the extension 193 and springs 197 in position to press the block 195 against its associated bearing block 191. When 25 the piston is driven by the blade, it will be obvious that the leading block 191 will be held in compression between the blade and the seat 189, in which said block is mounted. The trailing block, however, will not be in compression and 30 it is the function of the pressure means 195 and 197 to maintain the trailing block in snug sealing engagement with the blade 89. Should the device be arranged so that the pistons are driven by an external prime mover, the pressing means 35 195 and 197 would be arranged in position to co-operate with the leading block, since, if the piston be arranged to drive the cylinder, the trailing block will be in compression between the parts and the leading block will require to be 40 held in contact with the blade 89.

In the devices shown in Figures 1, 7, and 8, the several cylinders of the assembly receive the work medium through the common inlet including the duct 25 and the cylinders discharge into 45 the casing of the device operating as a receiver for the compressed work medium. It is, of course, within the contemplation of my present invention to transpose the intake and outlet ports 97 and 113 and drive the working members in 50 the opposite direction, i. e. in a counter-clockwise direction viewing Figure 3 in order that the work medium may be drawn into the cylinders from the casing and discharged under pressure through the common duct 25, thence through the channels 23 and 109 of the embodiment shown in 55 Figure 1, or through the channel 101 in the embodiment illustrated in Figure 8.

I may also arrange the compressor so that the cylinders operate separately, that is to say, the device may be arranged to draw the work medium into the cylinders through a separate intake for each cylinder and discharge the medium into the casing functioning as a common receiver for the compressed gases, or by driving the unit 60 in the opposite direction and making the appropriate changes in the inlet and discharge ports 97 and 113, the device may be arranged to draw the work medium into the cylinders from the casing and discharge the same through separate 65 discharge channels.

In Figure 9 of the drawings, I have shown a compressor adapted to function in this fashion. When the compressor cylinders are arranged with common intake and discharge spaces, as shown 70 in Figures 1 and 8, it is usually necessary and

preferable to make the cylinders so that each have the same fluid displacement. However, where the cylinders are arranged with either separate inlets or separate delivery conduits, it is usually desirable to form the cylinders of unequal 5 size, since the usual purpose of the construction is to provide different compression ratios in the several cylinders so that a single unit may be employed to produce a variety of positive or negative pressures. For example, the device of my 10 present invention may be utilized to deliver the work medium at or slightly above normal atmospheric pressures with the suction side of each cylinder drawing a different degree of sub-normal or vacuum pressures. Such a device will 15 have great value in a refrigerating system employing an evaporable medium, such as ammonia, carbon dioxide, ethyl chloride, as the work medium to be delivered by the compressor in a circulating system including evaporators arranged 20 in parallel and connected with the pressure side of the unit. In such a system, the suction side of certain of the evaporators may be connected with the intake to one cylinder of the unit while other evaporators may be connected to the suction intake of another cylinder of the unit so that 25 different evaporators of the system may be subjected to different degrees of vacuum pressure. In such an arrangement, the refrigerant will 30 evaporate more vigorously in those evaporators which are connected to the cylinder drawing the higher vacuum and consequently will absorb more heat. The obvious advantages of a single refrigerating system capable of producing different 35 rates of heat absorption are apparent and are made feasible as a practical matter by an application of my present invention.

As shown in Figure 9, the compressor comprises two cylinders 201 and 203 and co-operating pistons 205 and 207. The cylinder 203 and piston 40 207 are of the same diametral size as the cylinder 201 and piston 205, but are of lesser width so that the volumetric displacement of one cylinder per revolution of the device is less than that of the other. It is not, of course, essential to 45 change the volumetric displacement by varying the width of the cylinder since the same may be accomplished by altering the diameter of the parts without changing the width. It is, however, less expensive and simpler to control the 50 displacement of a cylinder by altering its width only, since this requires only the shaving down of a cylinder of standard diameter while to increase or decrease the diameter of the cylinder requires the fabrication of non-standard parts 55 with the additional expense of patterns and other manufacturing adjuncts. The pistons 205 and 207 shown in Figure 9 are illustrated in opposed relationship, and the piston supporting shaft will necessarily have a crank-like form. It is, however, entirely within my inventive concept to 60 arrange the pistons in the embodiment of Figure 9 in axial alignment as in the embodiments shown in Figures 1 and 8. Both of the cylinders 201 and 203 have outlet ports 211 corresponding with 65 the ports 113 of the embodiments previously described. These outlet ports vent through valves 215, similar to the valves 117, into the casing 15. Each cylinder also has an inlet port 217 corresponding with the ports 97 previously described, 70 but each port 217 connects with a separate duct 225 extending radially in the end plate 251. The ducts 225 each communicate with a separate channel 227 and 229 extending axially in the shaft 59, on which the cylinder assembly 11 is 75

carried. The cover extension 61 is provided with a removable partition 231 intermediate the end plate 62 and the partition 147, thus dividing the space between the partition 147 and the cover 5 plate 62 and providing separate chambers 233 and 235 on opposite sides of the partition 231. The axle 59 extends through the partitions 147, 231 and 62 and is provided with seal means 252 corresponding with the seal means 152 previously 10 described and functioning to seal the shaft against the passage of fluid from the chambers 233 and 235 along the shaft. The longitudinally extending channels 227 and 229 open respectively in the chambers 233 and 235. The walls of the 15 extension 61 also are provided with intake fittings 301 and 303 opening respectively in the chambers 233 and 235.

During the operation of the device, each cylinder will deliver compressed gases into the 20 housing 15 at the same pressure but the compression elements 201 and 205 will draw a pressure at the inlet fitting 301 substantially less than the pressure prevailing at the inlet fitting 303.

The lubricating system for the embodiment illustrated in Figure 9 may be substantially similar to that provided for the embodiment shown in Figure 8. If it is desired to build a compressor having a common inlet or suction and separate discharge outlets for the several cylinders, it is 30 simply necessary to transpose the outlet and inlet ports 211 and 217 and drive the device in the opposite direction.

It is thought that the invention and numerous 35 of its attendant advantages will be understood from the foregoing description and it is obvious that numerous changes may be made in the form, construction, and arrangement of the several parts of the illustrated apparatus without departing from the spirit or scope of my invention or sacrificing any of its attendant advantages, 40 the forms herein described being merely for the purpose of illustrating the invention.

Having thus described my invention, what I 45 claim as new and desire to secure by Letters Patent is as follows:

1. A device of the character described comprising cylinder means providing a plurality of pressure stages, piston means associated with each stage, said cylinder means having a projecting shaft fixed on an end wall thereof whereby the same may be supported for rotation about its axis, axially extending duct means in said shaft, blade means cooperatively associated with the cylinder means and the piston means in the several stages, said cylinder and piston means being operable to develop a pressure differential on opposite sides of the blade means in each of the stages when the cylinder means is rotated, said end wall carrying the shaft having a plurality of substantially radially extending ducts communicating each with one of the several stages and with said axially extending duct means.

2. A device as set forth in claim 1, wherein the piston means of the several stages are carried 65 on a common supporting shaft.

3. A device as set forth in claim 1, wherein the shaft includes a lubricant duct communicating with the interior of the cylinder means within the piston means in each stage, and means on 70 said shaft and operatively associated with said lubricant duct to deliver a lubricating medium within the several stages of the device.

4. A device of the character described comprising cylinder means providing a plurality of pressure stages, piston means associated with each

stage, a shaft fixed on and rotatably supporting said cylinder means, ducts in said shaft, each opening laterally thereof, certain of said ducts communicating each with at least one of said stages, a sleeve-like support receiving said shaft, 5 said support defining a plurality of adjacent chambers through which said shaft extends in position to communicate certain of the lateral openings of said shaft ducts each with at least one of said chambers.

5. A device as set forth in claim 4, including means for sealing said chambers against leakage along the shaft between adjacent chambers.

6. A pump or compressor comprising a cylinder element including a cylindrical wall and end walls extending substantially normal to the axis of the cylindrical wall, piston means within said cylinder element to define a working space within the cylindrical and normal walls, a shaft fixed on one of said normal walls, radial duct means 20 in one of said normal walls and opening into said work space, said duct means including a plurality of radially extending ducts, said shaft being formed with a plurality of axially extending channels therein, each channel communicat- 25 ing with a corresponding radial duct, the cylindrical wall of the cylinder element comprising a plurality of annular rings in axial alignment and defining separate working spaces within the element, and said piston means comprising a separate piston element in each work space of the assembly, said rings being formed with channels 30 communicating with said radially extending ducts and providing ports communicating with said work spaces.

7. A fluid flow device of the character described, comprising a cylinder element providing a plurality of rings in end to end relationship, each ring defining a compression space, a piston in each space, said cylinder element comprising 40 an end plate closing an end of one of said rings, a shaft fixed on said end plate and extending outwardly of said cylinder means, a sleeve-like support through which said shaft extends and in which the shaft is rotatably supported, means on 45 said sleeve-like support forming a plurality of adjacent chambers therein, longitudinal ducts in said shaft, opening one in each chamber and connecting each with a radial duct formed in said end plate, one of said radial ducts communicating through a channel in the rim of one of said rings with the work space defined by said ring, and the other radial duct communicating with another of said work spaces through aligned 50 channels formed in a plurality of said rings. 55

8. A device of the character described comprising cylinder means providing a plurality of pressure spaces forming stages, piston means in each stage, a blade cooperatively associated with the cylinder means and each of said piston means, 60 whereby to drivingly connect the piston and cylinder means for rotation about relatively eccentric axes to develop a pressure difference on opposite sides of the blade in each of said stages, a drive shaft fixed on said cylinder means for ro- 65 tatingly supporting and driving the same about its axis, said shaft being connected on an end wall of the cylinder means and having ducts in the shaft communicating, at the cylinder-connected end of the shaft, with radially extending 70 ducts within the end plate, said radially extending ducts communicating at the periphery of said end plate with longitudinally extending ducts formed in the cylindrical portion of said cylinder means, and each of the longitudinal ducts 75

opening through said cylinder means upon one of said pressure spaces adjacent the blade of said space.

9. A device of the character described comprising cylinder means providing a plurality of pressure spaces forming stages, piston means in each stage, blade means cooperatively associated with the cylinder means and each of said piston means whereby to drivingly connect the piston and cylinder means for rotation about relatively eccentric axes to develop a pressure difference on opposite sides of the blade means in each of said stages, a drive shaft fixed on said cylinder means for rotatably supporting and driving the same about its axis, said shaft being connected on an end wall of the cylinder means and having ducts

in the shaft communicating, at the cylinder-connected end of the shaft, with radially extending ducts within the end plate, said radially extending ducts communicating at the periphery of said end plate with longitudinally extending ducts formed in the rim of said cylinder means and each of the longitudinal ducts opening through said cylinder means upon one of said pressure spaces adjacent the blade of said space, said shaft extending through and supported in a sleeve-like housing, partition means defining chambers in said housing, the longitudinally extending ducts in the shaft each opening laterally of the shaft into one of said chambers.
